UNITED STATES PATENT OFFICE.

JAMES PEARSON, OF BROADHEATH, ENGLAND, ASSIGNOR TO LINOTYPE AND MACHINERY LIMITED, OF LONDON, ENGLAND.

TYPOGRAPHICAL DISTRIBUTING MECHANISM.

1,105,691.

Specification of Letters Patent.

Patented Aug. 4, 1914.

Application filed September 8, 1913. Serial No. 788,505.

To all whom it may concern:

Be it known that I, JAMES PEARSON, a subject of the King of the United Kingdom of Great Britain and Ireland, residing at Linotype and Machinery Works, Broadheath, in the county of Chester, England, have invented new and useful Improvements in Typographical Distributing Mechanism, of which the following is a specification.

This invention relates to improvements in the distributing mechanism of multiple font typographical machines using matrices similar to the matrices of the Mergenthaler machine now known commercially under the trade mark "Linotype," and consists in means by which any matrix of any font—but one of the fonts may advantageously be excepted—directly selects and practically establishes a temporary chute capable of leading it toward the distributor of the magazines from which it had been composed. The matrix of itself only selects the respective chute, the energy necessary to the practical establishment of the latter being derived, directly or indirectly, from one or more moving organs of the distributing mechanism.

The accompanying drawings show a preferred constructional form of the application of the invention to the distributing mechanism of one of the machines above mentioned, when equipped with six fonts each having its own magazine and distributor for character.

In them Figure 1, is a rear elevation; Fig. 2, a side elevation from the left of Fig. 1, and Fig. 3, a diagram showing the selecting function of a matrix of each of the six fonts.

1 is the composed line of matrices being subjected to distribution for font within the distributor box 2 fixed to the frame 3 of the machine. This line has been carried up from the previous stage in the operation of the machine, by the second elevator 4, and presented to the said box 2 by the elevator head 5 off which it was, thereupon, pushed on to the line-supporting devices in the box 2, by the pusher (not shown), which pushed it up to stops 6, 6, above which each leading matrix is successively raised by a lifter 7 on the end of a bell crank lever 8 fulcrumed at 9 on the box 2 and rocked in one direction by a cam 10 on a constantly rotating shaft 11, and in the other by a spring 12, the action

of the pusher, pushing the said matrix, through the following ones, up the inclines 13, 13^a from the tops of which latter it drops to find its way into one or the other of the six inclosed permanent chutes 14 to 19 leading to the respective distributor for character, all substantially in the well known way.

The above mentioned constructional form is located between the tops of the inclines 13, 13^a, and those of the chutes 14 to 19. 20, 65 21 are two of the four sides of a throat, the respective sides inclosing the chutes 14 to 19 being continuations of them. This throat is divided by five partitions 22 to 26 into six chutes 27 to 32, each partition being pivoted 70 by its bottom edge along the top edge of the respective partition between two adjacent chutes of the six, 14 to 19 as indicated at 33. The top of the throat side 21 is close to the box 2 and flush with the top of the bottom 75 inclines 13. This throat side 21 is serpentinized away therefrom toward the opposite side 20. The partitions 21 to 26 and side 20 are not parallel either with each other or with the side 21. They are all serpentinized, 80 each one more than its neighbor nearest to the box 2, the object being to position the pivot 33 nearest to the box 2 so far away from the latter that the weight the respective partition 26 will urge the top of it up 85 to the top of the side 21. The increased distances from the box 2, of the other partitions 22 to 25 does the like for them respectively, the top of the partition 22 being then vertically flush with the highest parts 90 of the inclines 13^a. The serpentinizing just described may be replaced by obliquity, but it is preferable to the latter for the reason that it avoids angles. The tops of the partitions of the chutes 14 to 19, start from the 95 bottoms of the partitions 22 to 26 respectively. When the partitions 22 to 26 are resting against the box 2, their tops are in the same horizontal plane which is a little above the highest level of the inclines 13. 100

The tops of the throat side 20 and of the two adjacent sides are continued upward above the highest possible position of the top of the next partition 22. The top of each partition 22 to 26 has its own distinctive contour. This distinctive contour is shown in Fig. 3 as consisting of recesses 34 producing projections 35. Each projection 35 is wider or narrower than any of the others and is preferably central on its par- 110

tion: Taking that on partition 22 as the widest, the others are gradually narrower in regular gradation, making that on partition 26—the first that a matrix would engage—the narrowest. Each font has its own distinctive contour. This distinctive contour is shown in the same figure, as consisting of a recess in the foot of each matrix, central to correspond with the central position of the projections 35. These recesses 36 to 41 are likewise graded in width, the narrowest being those of the matrices that must be led to chute 19, while the widest are those of the matrices that must be led to chute 14, the gradation being regular; each recess being narrower than the projection 35 on the partition beyond the chute 27 to 32 which a matrix must establish as it moves up the inclines 13, 13^a. Thus, say that the leading matrix must be led to the chute 17. It has a recess 39 and will find all the partitions 22 to 26 leaning against the box 2 with their projections 35 standing above the inclines 13. As its foot leaves the latter its recess 39 passes over the projections 35 on partitions 26 and 25 and engages that on partition 24 and rocks the latter before it, until the partition 25 is passed when the matrix will drop down the chute 30 which it has selected by itself and then practically established by energy derived from the above mentioned pusher. But there will be friction between both the flat sides of a matrix and the upper portions of the respectively adjacent partitions of the selected chute. To prevent this friction, the invention provides automatic means for opening the selected chute wide enough to allow the respective matrix to drop down it freely.

42 is a lever fulcrumed at 43 on a slide 44 adapted as by a slot 45 and studs 46, 46 to reciprocate horizontally on the distributor box 2.

47 is a bell crank lever fulcrumed at 48 on a lug 49 depending from the same box 2 and having the outer end of one arm pivotally connected to the nose of the lever 8 and that of the other arm by a slot and stud device 50 to the slide 44.

51 is a stud fast to the frame 3 above the fulcrum 43 and on the same side of the lever 42 as the throat side 20 and projecting into the path of the upper arm of the lever 42, the arrangement being such that the downward motion of the lever 8 which follows the elevation of the leading matrix above the stops 6, 6, and which motion practically coincides with the selection and establishment by that matrix, of the respective chute, acting through the connections just described, pushes the lever 42 toward the throat side 20, thereby making the engagement of its upper arm with the stud 51 rock its bottom end up to a lug 52 projecting laterally from the engaged partition, which latter the

leading matrix will have pushed past the normal position of that end, and rock the said partition and all the partitions between it and the throat side 20 up to the latter, as shown in Fig. 1. The next upward motion of the lever 8 returns the lever 42 and the connected parts to their normal position.

The invention includes the reversal of the respective positions of the series of recesses 36 to 41 and projections 35, that is to say, the former may be in the partitions 22 to 26 and the latter on the matrices or type dies, when the type of machine to which the invention is applied, allows of such reversal.

The terms "matrix", "matrices" are to be read throughout this specification and the claims as including "type die" "type dies" respectively.

Having described my invention I declare that what I claim and desire to secure by Letters Patent is:—

1. The combination with the font separating part of the distributing mechanism of a multiple font typographical machine and the permanent chutes therefrom to the respective parts for separating the matrices of each font according to character, of means enabling each matrix to select directly and by itself and practically establish a temporary chute for conducting it uninterruptedly to the respective permanent chute.

2. The combination with the font separating part of the distributing mechanism of a multiple font typographical machine and the permanent chutes therefrom to the respective parts for separating the matrices of each font according to character, of means enabling each matrix to select and practically establish a temporary chute for conducting it to the respective permanent chute and automatic means for opening the selected chute wide enough to allow a matrix to drop down it freely.

3. The combination with the font separating part of the distributing mechanism of a multiple font typographical machine and the permanent chutes therefrom to the respective parts for separating the matrices of each font according to character, of means enabling each matrix to select directly and by itself and practically establish a temporary chute for conducting it to the respective permanent chute and automatic means for opening the selected chute wide enough to allow a matrix to drop down it freely.

4. The combination with the font separating part of the distributing mechanism of a multiple font typographical machine and the permanent chutes therefrom to the respective parts for separating the matrices of each font according to character, of means enabling each matrix to select and practically establish a temporary chute for conducting it to the respective permanent chute

- and means actuated by the distributing mechanism for opening the selected chute wide enough to allow a matrix to drop down it freely.
5. In a typographical distributing machine, the combination of matrices each having a font-distinguishing contour, a plurality of distributers, a throat leading thereto, a series of independently pivoted partitions therein and having font distinguishing contours with which those on the matrices can coöperate.
6. In a typographical distributing machine, the combination of a fixed throat, a series of partitions independently pivoted therein, a vibrating lever, a reciprocating slide, a bell crank lever connecting both said lever and slide to reciprocate the latter, a lever fulcrumed on the said slide, and a fixed stud against which each alternate motion of the vibrating lever pushes one arm of the said fulcrumed lever thereby making it engage one of the partitions and push it before it.
25. 7. In a typographical machine the combination of different fonts of matrices, font separating mechanism, a plurality of distributers and means enabling each matrix to select directly and practically establish a temporary chute for conducting a matrix uninterruptedly from the font separating mechanism to one or another of the distributers.
8. In a typographical machine, the combination of different fonts of matrices, font separating mechanism, a plurality of distributers, means enabling each matrix to select and practically establish a temporary chute for conducting a matrix from the font separating mechanism to one or another of the distributers and automatic means for opening the selected chute wide enough to allow a matrix to drop down it freely.
9. In a typographical machine, the combination of a composed line of matrices, means for detaching and separating the matrices individually therefrom, a plurality of distributers, and movable means controlled in their movement by the matrices for conveying the separated matrices directly and uninterruptedly to one or another of the distributers.
10. In a typographical machine, the combination of a composed line of matrices, means for separating the matrices individually therefrom, a plurality of distributers, and movable intermediate switches controlled automatically in their movement by the matrices for directing them uninterruptedly to one or another of the distributers.
11. In a typographical machine, the combination of a line disintegrating mechanism, a plurality of distributers, a plurality of stationary chutes, one for each distributer, and a plurality of movable switches arranged between the chutes and the disintegrating mechanism, and each adapted to receive the matrices directly from the latter and convey them to their respective chutes, together with automatic means for operating the switches.
12. In a typographical machine, the combination of a composed line of matrices adapted to be separated individually from the line, a plurality of distributers, and a corresponding plurality of intermediate channels normally closed at their upper ends, and means whereby the matrices will effect directly the opening of their respective channels as they are separated from the line.

In witness whereof I have hereunto set my hand in the presence of two witnesses.

JAMES PEARSON.
